BELT CRADLE FOR ROVING AND SPINNING FRAMES

George West, Whitinsville, Mass., assignor to
Whitin Machine Works, Whitinsville, Mass., a
corporation of Massachusetts

Application March 26, 1937, Serial No. 133,228

10 Claims. (Cl. 19—131)

This invention relates to roving and spinning frames in which endless belts and aprons are provided for controlling the yarn fibers and for advancing the fibers from one pair of driving rolls to the next.

It is the general object of my invention to provide an improved cradle for supporting a pair of endless belts in association with the rolls of a roving or spinning frame, and for guiding the 10 belts in a desired path.

A further object is to provide a cradle which may be assembled in operative position without distortion or injury to the belts.

With these general objects in view, an important 15 feature of my invention relates to the provision of a cradle of simplified construction and having no loose or removable parts. Another feature relates to the provision of an improved means for guiding the belts, by which edge wear of the belts 20 is substantially eliminated.

My invention further relates to arrangements and combinations of parts which will be hereinafter described and more particularly pointed out in the appended claims.

25 A preferred form of the invention is shown in the drawing, in which—

Fig. 1 is a sectional side elevation of my improved cradle, in association with drawing rolls and endless belts;

30 Fig. 2 is a side elevation of the cradle;

Fig. 3 is a front elevation, looking in the direction of the arrow 3 in Fig. 2;

Fig. 4 is a plan view, looking in the direction of the arrow 4 in Fig. 2;

35 Fig. 5 is a sectional plan view, taken along the line 5—5 in Fig. 2;

Fig. 6 is a side elevation showing the parts in position for assembly;

Fig. 7 is a detail view of a guide bar; and 40 Figs. 8, 9 and 10 are detail views of modifications to be described.

Referring to the drawing, I have shown my improved cradle associated with a set of drawing rolls comprising a pair of back rolls 10, intermediate rolls 11 and front rolls 12. Upper and lower belts or aprons 13 and 14 are provided, which belts encircle the intermediate rolls 11 and at their front or lower ends are positioned by guide bars 15, one of which is shown in Fig. 7. 50 These bars form a part of the cradle to be described.

My improved cradle comprises side plates 20 and 21, a cross rod or stud 22, and a pair of the guide-bars 15 previously described. The stud 55 22 and guide-bars 15 are permanently assembled

with the side plate 20, these parts preferably having reduced end portions headed or spun to secure the stud and bars in the plate.

The outer end of the stud 22 also has a reduced portion 24 which forms a pivotal bearing 5 for the side plate 21, which plate also has openings 26 to receive the reduced and substantially rectangular outer end portions or projections 27 of the guide bars 15.

A stud or screw 30 having an enlarged head 10 31 is slidable in an axial opening in the stud 22 and extends into a recess 33 in said stud. A coil spring 34 is mounted on the stud within the recess 33 and is compressed between an end wall of the recess and a nut 35, threaded on the stud 30 and 15 freely slidable in the recess. After the nut has been adjusted by a suitable tool inserted in the recess 33, a cap 36 may be forced into the end of the recess to close said recess, as shown in Fig. 5.

The somewhat simpler stud construction shown in Fig. 8 may be substituted if desired. In this form, the stud 37 has a straight hole through which a headed bolt 38 extends. The bolt is secured by a nut 39 outside of the side plate 20. 25 This nut must be loosened before the cradle parts can be separated.

The side plates 20 and 21 have offset flanges 40 and 41 at their rear end portions, and also have their middle portions outwardly offset as 30 indicated at 42 and 43, all for a purpose to be described.

Having described the details of construction of my improved cradle, the manner of application and advantages thereof are as follows:— 35

When the cradle is to be applied in a roving or spinning frame, the parts are moved around to the position shown in Fig. 6, after which the lower guide-bar 15 is inserted in the lower belt 14, which has previously been mounted on the 40 lower intermediate roll 11.

The upper belt 13 is then placed over the upper guide bar 15 and the side plate 21 is swung around to the position shown in Fig. 2, in which position the projections 27 snap into the openings 26. The 45 parts are held in this assembled relation by the spring 34, acting through the stud 30 and its enlarged head 31.

It will be understood that the plate 21 assumes 50 the position shown in Fig. 5 only when manually displaced and held from return movement.

The upper belt is then in the dotted line position shown in Fig. 1, in which position the upper intermediate roll 11 is inserted in the belt. The 55

belt and roll are then swung downward to the operating position shown in Fig. 1.

It is sometimes desirable to vary the distance between the guiding portions of the bars 15, particularly as the nip of the belts 13 and 14 changes as the belts wear and become more flexible. To permit such adjustment, I may mount one or both of the guide bars as shown at 45 in Fig. 9. The bar 45 has a pivot portion 46 and a threaded portion 47, both located near one edge of the bar and loosely fitting pivot holes in the side plates. A nut 48 retains the adjustment.

Instead of mounting both guide bars on the plate 20, I may mount one bar 15^a on the plate 15 20 and the other bar 15^b on the plate 21, as shown in Fig. 10.

Reference to Fig. 1 will show that the belts are guided laterally by the end portions 50 of the side plates 20 and 21, which end portions 50 engage the belts as they pass around the guide bars 15 and while they are approaching but still clear of the rolls 11. Those portions of the belts which are gripped between the rolls are not engaged by the side plates, by reason of the 25 outwardly displaced portions 42 and 43.

I thus guide the belts in desired paths by engagement with those portions of the belts which are approaching the rolls but not yet under pressure and which may be readily shifted laterally 30 if necessary, while on the other hand no lateral or transverse pressure is applied to those portions of the belts which are under pressure and which are incapable of yielding transversely. Consequently the belts are easily and accurately 35 guided and there is practically no wear on the edges of the belts, as is the case where the side plates engage those portions of the belts which are under pressure.

The flanges 40 and 41 are provided to limit 40 side travel of the roving R by engagement therewith, as indicated in Fig. 1, so that the roving may not traverse so far in either direction as to run off of the edges of the belts.

The advantages of my improved cradle will be 45 readily apparent. In the first place, there are no loose parts to be removed and replaced and consequently to be readily lost. In the second place, the straight and unobstructed guide-bars 15 are easily inserted within the belts by a simple 50 straight movement, so that no stretching or distortion of the belts is occasioned by either assembly or separation of the parts. Furthermore, the extreme simplicity of the assembled structure assists greatly in maintaining the desired 55 cleanliness of the machine.

Having thus described my invention and the advantages thereof, I do not wish to be limited to the details herein disclosed, otherwise than as set forth in the claims, but what I claim is:—

60 1. A cradle for endless belts in a roving or spinning frame comprising a side plate, a cross stud fixed thereto, a second side plate movably mounted on the outer end of said cross stud, a pair of guide-bars each secured in one of said side plates and having locating engagement with the other side plate, and means to hold said parts in operative relation.

65 2. A cradle for endless belts in a roving or spinning frame comprising a side plate, a cross stud fixed thereto, a second side plate movably mounted on the outer end of said cross stud, a pair of guide-bars secured in said first side plate and having locating engagement with said second plate, and means to hold said parts in operative relation.

70 3. A cradle for endless belts in a roving or spinning frame comprising a side plate, a cross stud fixed thereto, a second side plate pivoted on the outer end of said cross stud and having openings therein, a pair of guide-bars secured in said first side plate and having projecting end portions insertable in said openings in said second plate, and yielding means to hold said parts normally in operative relation and to prevent disassembly of said parts.

75 4. A cradle for endless belts in a roving or spinning frame comprising a side plate, a cross stud fixed thereto, a second side plate movably mounted on the outer end of said cross stud, said side plates having openings therein, a pair of guide-bars each secured in one of said plates and having a projecting end portion insertable in an opening in the other plate, and means to hold said parts in operative relation, one of said guide bars being angularly adjustable in said 20 side plates and means being provided to preserve the angular adjustment of said bar.

80 5. A cradle for endless belts in a roving or spinning frame comprising a side plate, a cross stud fixed thereto, a second side plate pivoted 25 on the outer end of said cross stud and having openings therein, a pair of guide-bars secured in said first side plate and having projecting end portions insertable in said openings in said second plate, and yielding means to hold said parts 30 in operative relation, one of said guide bars being angularly adjustable in said side plates and means being provided to preserve the angular adjustment of said bar.

85 6. A cradle for endless belts in a roving or spinning frame comprising a side plate, a cross stud fixed thereto, a second side plate pivoted 40 on the outer end of said cross stud, said plates having openings therein, a pair of guide-bars secured in one of said side plates and having projecting end portions each insertable in said openings in said side plates, and a spring-operated 45 plunger mounted in said cross stud and effective to hold said parts normally in operative relation.

90 7. A cradle for endless belts on drawing rolls 45 in a roving or spinning frame comprising a cross rod, a pair of guide-bars, a pair of side plates spaced apart by said rod and bars, and means to hold said parts normally in operative relation, said side plates having portions engaging and transversely guiding the belts at points only 50 where said belts are free from pressure and having all portions adjacent the belts as they approach or engage the drawing rolls offset outwardly to clear the edges of said belts.

95 8. A cradle for endless belts in a roving or spinning frame comprising a cross rod, a pair of guide-bars, a pair of side plates spaced apart by said rod and bars, and yielding means to hold 60 said parts in assembled relation, said side plates having portions engaging and transversely guiding the belts at positions where said belts are approaching the rolls and are free from pressure, and having other portions clearing the edges of 65 said belts at positions where the belts are leaving the rolls and are under pressure.

100 9. A cradle for endless belts in a roving or spinning frame comprising a fixed one-piece side plate, a movable one-piece side plate, a cross rod permanently and pivotally connecting said 70 side plates, and two guide bars each fixed in one of said plates, all of said parts being permanently 75 assembled but one of said side plates as a unit being pivotally mounted relative to the other side plate on said cross rod, means to determine the 75

normal operative position of said pivoted side plate, and means to hold said pivoted plate in operative position but permitting manual displacement thereof.

5 10. A cradle for endless belts in a roving or spinning frame comprising two side plates, a

pair of belt guide-bars spaced apart and located in and between said side plates, one of said guide bars being angularly movable to selectively vary the spacing between said guide-bars, and means to maintain a selected spacing of said bars.
